S. PAULL.
BATHING SUIT POCKET.
APPLICATION FILED JUNE 4, 1915.

1,164,010.

Patented Dec. 14, 1915.

UNITED STATES PATENT OFFICE

SAMUEL PAULL, OF NEW YORK, N. Y.

BATHING-SUIT POCKET.

1,164,010.

Specification of Letters Patent. Patented Dec. 14, 1915.

Application filed June 4, 1915. Serial No. 32,046.

To all whom it may concern:

Be it known that I, SAMUEL PAULL, a citizen of the United States, and residing at New York, in the county of New York and State of New York, have invented certain new and useful Improvements in Bathing-Suit Pockets, of which the following is a specification, such as will enable those skilled in the art to which it appertains to make and use the same.

This invention relates to pockets for bathing suits, and the object thereof is to provide a device of this class which is adapted to be connected with a bathing suit, or a body garment forming part of a bathing suit in such manner that the head portion of the pocket may be outside of the garment and may be opened for the insertion or removal of various articles into and from the pocket whenever necessary or desirable; a further object being to provide a device of the class specified which will be waterproof and which may be used in connection with bathing suits of any kind or class; and with these and other objects in view the invention consists in a device of the class specified and applied and operated as hereinafter described.

The invention is fully disclosed in the following specification, of which the accompanying drawing forms a part, in which the separate parts of my improvement are designated by suitable reference characters in each of the views, and in which:—

Figure 1 is a side view of my improved bathing suit pocket detached from the garment and independent of the head or jaw members and with parts broken away; Fig. 2 a section on the line 2—2 of Fig. 4 but showing the pocket attached to the garment; Fig. 3 another sectional view of the top portion of the pocket on an enlarged scale but showing only the pocket proper, the head or jaw members by which the pocket is closed and opened when in use being not shown; Fig. 4 a plan view of the pocket complete and on an enlarged scale and with parts broken away, and showing the head or jaw members in position; and, Fig. 5 a plan view of the pocket complete and showing it open.

In the drawing forming part of this specification, I show at *a* a part of a bathing garment, or the body portion thereof and, in the practice of my invention, I provide a pocket *b*, comprising a part *b*² of rubber, an

outer casing *b*³ of fabric and a fabric lining *b*⁴. The sides of the outer casing *b*³ of fabric are provided with flaps *b*⁵ which are preferably formed integrally with said outer casing, and between the top portion of the outer fabric casing *b*³ and the rubber pocket member *b*² is placed a strip *c* of fiber, or fibrous material and rubber. The fabric lining *b*⁴ does not extend to the top of the pocket or to the top of the rubber part *b*² and placed in the top of the pocket and vulcanized to the top of the rubber part *b*² of the pocket and to the top of the lining *b*⁴ is a thick rubber band *d*, and the parts *b*² and *b*³, and *b*⁵ are stitched together at the top of the pocket as shown at *b*⁶ by two lines of stitching extending around said pocket. This completes the pocket construction independent of the head or jaw members *e* which in this case are made detachable. The jaw members *e* which form the detachable head of the pocket are composed of two separate parts *e*² of the same length and pivoted together at *e*³, and said jaw members *e* are hinged together at *e*⁴, this connection preferably consisting of block-shaped devices hinged or pivoted to the ends of the jaw members at *e*⁵, and the separate parts *e*² of one jaw member *e* are provided with inwardly directed flanges *e*⁶, in the form of construction shown, while the separate parts of the other jaw member consist only of bars *e*⁷, and one of the jaw members *e* is provided adjacent to the hinged connection at *e*³ with a pivoted U-shaped clamp *f*, and when the separate jaw members *e* are closed together, as shown in Fig. 4, the clamp *f* is swung down into its operative position, as shown in Fig. 2, and securely locks the jaw members *e* together and the construction of the jaw members and the location of the clamp *f* is such that when said clamp is swung into its operative position it incloses the hinge connection *e*³ of the separate parts of the jaws *e*. The garment *a* is provided with a slot or opening at *a*², and in connecting my improved pocket with the garment, the top of the pocket is inserted between the jaw members *e* which are separated to permit of this operation, and the clamp *f* is swung down into operative position and this securely binds the top of the pocket in the head or jaw members, and the body portion of the pocket is passed inwardly through the slot or opening *a*² and the flaps *b*⁵ at the top of the pocket are stitched, or otherwise se-

cured to the garment above the slot or opening α^2 . With this construction, the pocket is secured in the garment and can only be detached by breaking the connection between 5 the flaps b^5 and the garment, but the head of the pocket is outside of the garment and said pocket may be opened by raising the clamp device f , after which the jaws may be swung outwardly or laterally, as shown 10 in Fig. 5, and any desired article or articles may be placed in, or removed from the pocket or pockets, and the pocket may be closed by pressing the jaw members together and swinging the clamp f into its operative 15 position.

The jaw members e when in operative position as shown in Figs. 2 and 4, compress the thick rubber band d , or the opposite sides thereof together, and the top of the 20 pocket is sealed against the entrance thereto of water, and when the pocket is closed the flanges e^6 of one jaw member, or the separate parts thereof, overlap the other jaw member, or the separate parts thereof. 25 With this construction the head may be detached from the pocket at any time and may be detached from said pocket in the operation of placing articles in, or removing articles from the said pocket, and said 30 head may be connected with the pocket whenever desired by simply slipping the open end of the pocket into the head, or between the jaws thereof. My invention, however, is not limited to the exact form of 35 the separate jaw members e , or the separate parts thereof, as herein shown and described, nor to any particular method of hinging or connecting the jaw members e at the ends thereof and any suitable hinge 40 device may be substituted for the blocks e^4 , and other changes in and modifications of the shape or form of the jaw members e and the method of connecting the same as well as in the construction of the pocket may 45 be made, within the scope of the appended claims, without departing from the spirit of my invention or sacrificing its advantages.

In compliance with rule 43 reference is 50 hereby made to my copending application Serial No. 32,478, filed June 7, 1915.

Having fully described my invention, what I claim as new and desire to secure by Letters Patent, is:—

1. A pocket of the class described, comprising a part of rubber provided with a fabric outer casing and a fabric lining, said pocket being provided within the open end thereof with an inner packing band of rubber which is secured to the top of the rubber part and to the top of the lining, and the top of the pocket being also provided with depending side flaps and between the outer fabric casing and the rubber part with a fibrous strip which is also secured to the 65 rubber part.

2. A pocket of the class described, composed of inner and outer fabric members between which is a part of rubber, said pocket being provided in the top or open 70 end thereof with an annular packing band of rubber and at the sides of the top thereof with depending flaps, and a head into which the top or open end of the pocket is adapted to be detachably inserted, said head 75 consisting of separate jaws hinged together at their opposite ends, said jaws being composed of separate parts also hinged together, and a clamp device connected with one of said jaws and adapted to lock them in a 80 closed position.

3. A pocket for use in connection with a bathing garment and provided with a detachable head, comprising separate jaws 85 hinged together at their ends and composed of separate parts also hinged together, said jaws being provided with means for locking 90 them in their closed position.

4. A bathing suit garment provided with a pocket the open end of which projects 90 from said garment and is provided with a detachable head, consisting of separate jaws hinged together at their ends and adapted to be opened and closed.

In testimony that I claim the foregoing 95 as my invention I have signed my name in presence of the subscribing witnesses this 2nd day of June, 1915.

SAMUEL PAULL.
